United States Patent Office

Des. 201,479

Patented June 22, 1965

201,479

WRITING INSTRUMENT HOLDER

Hiram Jackson Green, 7 Homan Terrace,
Daytona Beach, Fla.

Filed May 19, 1964, Ser. No. 80,053

Term of patent 14 years

(Cl. D74—21)

FIG. 1 is a perspective view of a writing instrument holder incorporating the design of the present invention;

FIG. 2 is a top plan view of the device shown in FIG. 1;

FIG. 3 is a front elevational view of the device shown in FIG. 1;

FIG. 4 is a bottom plan view of the device shown in FIG. 1;

FIG. 5 is an end elevation thereof as seen from the right of FIG. 3;

FIG. 6 is an end elevation thereof as seen from the left of FIG. 3; and

FIG. 7 is a rear elevational view of the device shown in FIG. 1.

I claim:

The ornamental design for a writing instrument holder, as shown and described.
